UNITED STATES PATENT OFFICE.

JAMES P. RICHARDSON, OF MANILA, PHILIPPINE ISLANDS.

BASE.

1,185,438.

Specification of Letters Patent.

Patented May 30, 1916.

Application filed September 13, 1915. Serial No. 50,452.

To all whom it may concern:

Be it known that I, JAMES P. RICHARDSON, a citizen of the United States, residing at Manila, in the Territory of Philippine Islands, have invented certain new and useful Improvements in Bases; and I do hereby declare the following to be a full, clear, and exact description of the invention, such as will enable others skilled in the art to which it appertains to make and use the same.

This invention relates to improvements in bases for the various types of printing plates and to the method of producing same and is particularly designed as an improvement on the base described and claimed in my co-pending application filed February 4, 1915, and serially numbered 6117.

It is my purpose to provide an improved base formed of a plurality of independent units which are graduated in size by a table of measurements so as to enable them to be readily combined to produce a desired standard size base.

It is my further purpose to provide a base which will be proof against warping, whose surface is unaffected by swelling of the individual units as a result of absorbing moisture, which has a complete metal binding around all its sides making perfect surfaces for lock-up with other type matter and material.

It is also my purpose to provide an improved process for forming bases with mortises of any dimensions or configuration and with a complete metal wall without the necessity of cutting or piercing the base.

With these and other purposes in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a view in elevation of a base constructed in accordance with the invention; Fig. 2, an edge view of same; Fig. 3, a horizontal section through the base, Fig. 4, a horizontal section through one of the corner units; Fig. 5, a horizontal section through one of the intermediate edge units; Fig. 6, a horizontal section through one of the interior units; Fig. 7, a view in elevation

of a base constructed with mortises and before the blanks are removed; Fig. 8, a view similar to Fig. 7 after the blanks which form the mortises are removed, and Fig. 9, a view 60 in elevation of a base before the adjacent edges of the units are cut away to dispose said edges in spaced relation.

Referring to the drawings and particularly to Figs. 1, 2, 3, 4, 5, 6 and 9 it will be 65 seen that the base is formed of a plurality of wooden units A of three types namely corner units 10, intermediate edge units 11 and interior units 12. The corner units have all of their side edges provided respectively 70 with grooves 13, the grooves in the outer side edges being of greater depth than the grooves in the inner side edges. The intermediate edge units 11 also having their side edges provided with grooves 14 and the 75 groove in the outer edge of these units is of greater depth than the remaining grooves. Likewise the interior units 12 have their side edges provided with grooves 15 all of equal depth. By providing the relatively deep 80 grooves 13 and 14 a strong complete metal binding is provided around the base as will hereinafter appear. It will be noted that the various grooves in the units are of greater width than depth and as a result greater 85 strength with less metal filler in the finished base will be had. The bases of all the grooves 13, 14 and 15 are provided with recesses 16 which are also adapted to receive the metal filler to be hereinafter referred to. 90

In forming the base the requisite number of units A are set up in the angle of a square and bearers placed around three sides of the assembled units. The casting box is then closed and molten metal poured into the 95 various grooves and recesses previously described with the result that a base similar to that shown in Fig. 9 is formed. In this way a rough unfinished base is produced but it could be subsequently planed and trimmed 100 and a strong serviceable base would be the ultimate result. It has been found however that the wooden units in a base similar to that shown in Fig. 9 on absorbing more or less moisture will swell and where the edges 105 of the units come in contact small ridges will form causing an uneven surface. As a result of this condition I find it advantageous to subject the base to additional treatment and to this end I cut grooves between the 110 units down to the metal filler as clearly shown at 17 in Fig. 1. These grooves 17

form a space to allow for the swelling without affecting the surface. In this manner I positively obtain a base that is not affected by warping or swelling.

5 It will be noted that by making the grooves in the various units relatively wide the reinforcing qualities of the metal filler or binder are materially enhanced with the use of less metal than was necessary in the 10 structure set forth in my previous application. It will also be noted that by providing the recesses 16 I prevent the units becoming detached, especially the corner units.

In forming bases of irregular shape and 15 with mortises I employ blanks 18 as clearly shown in Figs. 7 and 8. These blanks are assembled with the units in the desired manner and when the metal is poured it will surround the blank and upon removal of the 20 latter either an opening or an irregular edge will be provided having a metal face.

While I have illustrated and described one form of carrying the invention into 25 practice it will be noted that various changes can be resorted to without departing from the spirit of the invention as set forth in the appended claims.

What is claimed is:—

30 1. A printing plate base comprising a non-metallic body formed of a plurality of independent sections each of which has communicating grooves in the various faces, said grooves being of greater width than depth and the grooves of one section being disposed in registration with the grooves in adjacent sections, and a metallic filling in 35 said grooves.

Copies of this patent may be obtained for five cents each, by addressing the "Commissioner of Patents, Washington, D. C."

2. A printing plate base comprising a non-metallic body formed of a plurality of independent sections each of which has communicating grooves formed in the various faces, the grooves of one section being disposed in registration with the grooves in adjacent sections, and a metallic filling in 40 said grooves, the adjacent edge of the section being cut away to dispose same in spaced relation.

3. A printing plate base comprising a non-metallic body formed of a plurality of independent sections each of which has communicating grooves formed in various faces and recesses opening through the bottoms of said grooves, the grooves of one section being disposed in registration with the 45 grooves in adjacent sections, and a metallic filling in said grooves.

4. The method of forming printing plate bases consisting of providing a plurality of sections with communicating grooves in various faces and with recesses opening through the bottom of said grooves, securing 50 said sections together edge to edge with the grooves of one section in registration with corresponding grooves of adjacent sections, filling said grooves with metal, and then cutting away the adjacent edges of the sections to dispose said edges in spaced relation.

In testimony whereof, I affix my signature, in the presence of two witnesses.

JAMES P. RICHARDSON.
